UNITED STATES PATENT OFFICE.

DAVID H. LAMAR, OF HUTCHINSON, WEST VIRGINIA.

RECIPROCATING IMPACT TOOL.

Application filed December 3, 1921. Serial No. 519,727.

To all whom it may concern:

Be it known that I, DAVID H. LAMAR, a citizen of the United States, residing at Hutchinson, in the county of Marion and State of West Virginia, have invented new and useful Improvements in Reciprocating Impact Tools, of which the following is a specification.

This invention relates to electrically operated mining machines of that character which may be used in the capacity of a pick, hammer, drill or the like, and provides a construction wherein the motion of the plunger rod can be quickly and conveniently changed from a sliding to a combined sliding and rotary motion as the occasion requires.

Another object of the invention resides in providing a machine of this character which is very simple in construction, embodying a minimum of parts, but at the same time strong and durable, the parts being related to eliminate the jerks and rebounds which are experienced with the use of other tools of this character, and which often results in injury to the user.

The nature and advantage of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:—

Figure 1 is a view in elevation constructed in accordance with the invention.

Figure 2 is a longitudinal sectional view through the machine.

Figure 3 is a fragmentary view through the machine, showing the position of the parts when it is desired to change the motion of the plunger for use as a drill.

Figure 4 is a transverse sectional view taken on line 4—4 of Figure 2.

Figure 5 is a transverse sectional view taken on line 5—5 of Figure 2.

Figure 6 is a fragmentary sectional view of the inner casing showing the grooves therein.

The machine forming the subject matter of the present invention comprises an outer casing 10 and an inner casing 11, the said casings being spaced apart to define a cham-

ber for the reception of the solenoids 12 and 13 respectively. The casing 10 is extended to provide a reduced end portion 14 thereby defining a shoulder 15, and the adjacent extremity of the inner casing 11 is embedded in this shoulder as at 16. The outer ends of these casings are closed by a cap 17 equipped with a handle 18. Supported by the cover 17 is a switch box 19 in which is arranged a movable switch element 20 which is controlled by a thumb lever 21 which is arranged in juxtaposition to the handle 18.

Arranged to operate within the casing 11 is a magnetic core 22 which is equipped with a packing ring 23 and also formed with an enlarged recess 24 which opens at one end of the core as shown. The recess 24 communicates with a longitudinally disposed bore 25 extended through the core 22 and also through the plunger rod 26 which has one end threaded into the magnetic core. Operating within the recess 24 is an air gate 27, the latter cooperating with an air gate 28 controlling an opening 29 in the cover 17, the construction and arrangement being such that the gates alternately open and close incident to the operation of the machine to maintain the hole being drilled or formed free from dust as will be readily understood. However, when the machine is used as a pick or a hammer, as in contradistinction to a drill, the lock screw 30 is adjusted to render the gate 28 inoperative. Positioned within the reduced end portion 14 of the casing 10 is a buffer 31 and arranged adjacent this buffer is a guide block 32 having a bore through which the plunger rod 26 operates.

A disk 33 is formed with a central opening to receive the hollow boss 34 which projects from one end of the guide block 32 and threaded on the hollow boss is a ring 35. Surrounding the boss 34 and having one end bearing against the ring 35 is a coiled spring 36, the opposite end bearing against the disk 33 to hold the latter normally in contacting engagement with the adjacent end of the guide block 32. The adjacent faces of the guide block 32 and the disk 33 are serrated, or in other words, formed with cooperating teeth to provide for a rigid lock between these parts so that they are held immovably associated for a purpose to be hereinafter described. The teeth of these parts are indicated at 37.

Threaded into the reduced end of the casing 10 is a bearing 38 for the plunger rod. Supported by the outer end of the plunger rod and providing a connection between the latter and the shank 39 of the tool to be used therewith is a cylindrical or sleeve-like member 40, and supported by this sleeve, is what I term a governor box 41 containing spaced contacts, 42 and 43 respectively and a movable contact 44 which is pivoted at one end between the contacts 42 and 43. The movable contact 44 supports a weight 45 at one end. The contact 42 is connected by means of a wire 47 with the solenoid 12, while the contact 43 is connected by means of a wire 46, with the solenoid 13, while an intermediate wire 48 establishes connection between the switch 19 and the movable switch element 44 as illustrated. Arranged within the casing 11 and supported by the casing 17 is a check spring 49 disposed in the path of movement of the magnetic core 22. The opposite end of this core is recessed to receive a cushioning element 50 which surrounds the plunger rod 26 which is adapted to be brought into contact with the ring 35 upon the power stroke of the said rod 26. It will be noted that the magnetic core 22 further serves in the capacity of a weight to drive the rod 26 with considerable force on its power stroke.

The operation of the machine thus far described is as follows:

When the thumb lever 21 is depressed, the switch 19 is closed, thereby energizing the movable switch element 44 which operates within the governor box 41. The movable switch element 44 which is weighted at one end is arranged to oscillate and to alternately engage the contacts 42 and 43 respectively, and in this manner alternately energizes the solenoids 12 and 13 respectively. For instance, when the tool 39 carried by the plunger rod 26 is brought into contact with the work, the sudden stop of the tool will cause the movable contact 44 to oscillate or fall upon the contact 43, thereby energizing the solenoid 13 which would move the magnetic core from the forward end of the machine to the rear end thereof and return the plunger rod 26 to its initial position. When the magnetic core 22 reaches the limit of its movement or travel in this direction, the movable contact 44 is automatically shifted into engagement with the contact 42, thereby energizing the solenoid 12 for another power stroke of the plunger rod 26. In this manner, the operation of the machine is continued with the plunger rod reciprocating through the guide 32. By reason of the construction and arrangement of parts, it is obvious that a stroke of the plunger rod 26 is immediately stopped upon striking the

object and the solenoid 13 energized to return the plunger rod to its normal position, so that kicks and rebounds, which frequently prove injurious to the operators of machines of this kind are practically eliminated.

As above stated, the motion of the plunger can be changed to permit of the use of a drill, and for this purpose, the guide block 32 is provided with a radial bore 52 which receives a threaded bolt or the like 53. The normal position of this bolt is that shown in Figure 2, and when it is desired to change the motion of the plunger rod for the purpose stated, the bolt is threaded into a notch 54 formed in the plunger rod 26. This manifestly, locks the guide block 32 to the plunger rod 26, for movement therewith so that when the plunger rod 26 is retracted or moved within the casing 11, the disk 33 moves also with the plug within said casing. The casing 11 is formed with spiral grooves 55, and operating in these grooves are projections 56 which radiate from the disk 33. Consequently, when the disk 33 is moved within the casing 11, the guide lock 32, disk 33 and plunger rod 26 is slightly rotated. The teeth 37 carried by the guide block 32 and the disk 33 prevent relative movement between these parts while they are being moved within the casing 11 for the purpose stated, but on the power stroke of the plunger rod, the latter moves forwardly together with the guide block 32 independently of the disk 33. By reason of this construction, the drill is slightly turned with each operation, so as to prevent its cutting edge striking in the same pit on each stroke, and the grooves 55 are so disposed as to completely revolve the plunger rod in about eight strokes of the latter.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:

1. A machine of the character described comprising a casing, a plunger rod arranged to reciprocate within the casing and projecting from one end thereof, a guide through which said rod slides, means for actuating said rod, means for securing the guide to the rod for movement therewith, and cooperating means associated with the said guide and casing, whereby the motion of said rod is changed from a sliding to a rotary motion for the purpose specified.

2. In a machine of the character described, a casing, a plunger rod projecting from one end of the casing and arranged to reciprocate therein, a normally station-

ary guide arranged within the casing and through which said rod slides, means for operating said rod, means for securing the guide to said rod for movement therewith, 5 a disk normally arranged in face to face contact with said guide, yieldable means for holding said parts so associated, said casing having spiral grooves, and means carried by said disk and movable within said grooves to change the motion of said rod from a sliding to a rotary motion when said rod moves in one direction. 10

In testimony whereof I affix my signature.

DAVID H. LAMAR.
